UNITED STATES PATENT OFFICE.

HARRY PAGE MAUS AND DODE M. LAMSON, OF LIMA, OHIO, ASSIGNORS TO THE PAGE ORGAN COMPANY.

SECTIONAL PIPE CHEST.

Application filed September 20, 1926. Serial No. 136,614.

This invention relates to sectional or individual pipe chests for pipe organs and the like, and has for its object to provide a plurality of separate chests, any number of which may be assembled when building an organ, depending of course upon the particular type and size of organ desired.

In the present state of the art the pipe chests are built up as a single unit and divided into separate compartments by a plurality of partitions. It will thus be seen that since practically no two organs are identical it is impossible to build these chests in advance of the receipt of the specifications for the particular organ desired. This of course, requires considerable time and therefore gives rise to a delay of several weeks in filling an order for any particular organ. It is the purpose of the present invention to obviate this delay in filling an order for a special type of organ by providing sectional pipe chests which may be kept in stock and quickly assembled on a standard or adjustable frame, the number of sectional chests employed depending on the particular requirements set forth in the specifications.

It is also an object of the present invention to provide an adjustable frame and adjustable wind conveyor which may be lengthened or shortened to correspond to the number of sectional chests employed in constructing the organ.

Other objects and advantages of the invention will be apparent from the following description when taken in connection with the accompanying drawings in which,

Figure 1 is a perspective view of a standard frame showing the sectional chests assembled thereon and a few of the pipes in position.

Figure 2 is a perspective view of an adjustable frame and wind conveyor and showing the same partly extended so as to receive an increased number of the sectional chests.

Figure 3 is a fragmentary perspective view of the adjustable frame and showing several of the sectional chests in dotted outline, and;

Figure 4 is a fragmentary bottom plan view of one of the sectional chests.

Referring to the drawings more in detail and particularly to Figure 1 of the drawings, the numeral 1 indicates a standard frame provided with the usual pressure

equalizer 2 and wind conveyors 3 and 4 by which the wind is conveyed from the equalizer to the sectional chests mounted on the top of the frame.

These sectional chests, which as hereinbefore indicated are prepared in advance and assembled according to specifications, are designated by the numeral 5. The chests 5 are horizontally arranged upon the top of the frame 1 and are operatively connected to the standard wind conveyor 4, in the same manner as is employed when using the well-known compartment wind chest. The wind chests are preferably attached to the sides of the frame 1 by dowel pins or the like, as will be hereinafter described in connection with the description of the form illustrated in Figures 2, 3 and 4.

Mounted on top of each of the sectional wind chests 5 is a rack or frame 6 which is supported by means of the end plates 7, and which forms a brace for the pipes 8, communicating with the wind chests.

In the preferred form of the invention shown in Figures 2, 3 and 4 (Sheet 2) the frame 10 is made adjustable so that these also may be prepared in advance and kept in stock. To this end the frame 10 is provided with auxiliary side plates 11 which are mounted for sliding movement with respect to the main side plates 12, and which are provided with auxiliary legs 13 much after the manner of an extensible table. In this embodiment of the invention the wind conveyor 14 is also rendered adjustable by providing a telescopic section 15 which is slidably associated with the main section 14.

The sectional wind chests 16 disclosed in Figures 2 to 4 inclusive are identical with those previously described except for the fact that they are provided with two sets of holes 17 and 18 which are adapted to receive dowel pins 19. The outer set of holes 17 are of course, employed when the wind chest is mounted on the main frame and the inner set 18 when the wind chest is mounted on the extensible portion of the frame as clearly indicated in Figure 3.

In this latter form of the invention the sectional wind chests are also provided with racks 20 adapted to form supports for the pipes (not shown).

From the foregoing description taken in connection with the accompanying drawings it will be observed that we have devised an

extremely novel construction of wind chests and frames for pipe organs and the like, by means of which these parts may be kept in stock and quickly assembled to provide the desired number of pipes depending upon the requirements of the particular order to be filled.

In accordance with the patent statutes we have described what we now believe to be the best embodiment of the invention, but we do not wish to be understood thereby as limiting ourselves or the scope of the invention, as many changes and modifications may be made without departing from the spirit 15 of the invention; all such we aim to include in the scope of the appended claims.

What we claim as new and desire to secure by Letters Patent is:

1. In a pipe organ, a frame for supporting wind chests, said frame including a pair of main side plates, a pair of auxiliary side plates slidably connected thereto, and legs mounted on the free ends of said auxiliary side plates.
2. In a pipe organ, a frame for supporting wind chests, said frame including a pair of main side plates, a pair of auxiliary side plates, and an extensible wind conveyer associated with said main and auxiliary side plates.
3. In a pipe organ, a frame for supporting

wind chests, said frame including a pair of main side plates, a pair of auxiliary side plates slidably connected thereto, and an extensible wind conveyer comprising telescopic tubes one of which is secured to one of the main side plates and the other of which is secured to the corresponding auxiliary side plate.

4. In a pipe organ, a frame for supporting wind chests, said frame including a pair of main side plates, a pair of auxiliary side plates slidably connected thereto, legs on the free ends of said auxiliary side plates, and an extensible wind conveyer having one portion secured to one of the main side plates, and the other portion secured to the corresponding auxiliary side plate.

5. In a pipe organ, a frame for supporting wind chests, said frame including a pair of main side plates and a pair of auxiliary side plates slidably associated therewith, fastening means formed on the upper edges of said main and auxiliary side plates, a plurality of separate wind chests, each wind chest being provided with two sets of attaching means at each end thereof so as to cooperate either with the fastening means on the main side plates or on the auxiliary side plates.
